(57) **CLAIM**

The ornamental design for a combination sign and rear brake light, as shown and described.

DESCRIPTION

FIG. 1 is a perspective view of a combination sign and rear brake light, showing my new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a right side elevational view thereof, the left side elevation view being a mirror image thereof.
